UNITED STATES PATENT OFFICE.

MAURICE J. SCHLESS, OF NEW YORK, N. Y., ASSIGNOR TO SCHLESS HARWOOD CO., OF NEW YORK, N. Y., A FIRM COMPOSED OF MAURICE J. SCHLESS AND WALLACE W. HARWOOD.

DESIGN FOR A RING.

Application filed July 15, 1927. Serial No. 22,755. Term of patent 14 years.

To all whom it may concern:

Be it known that I, MAURICE J. SCHLESS, a citizen of the United States of America, residing at New York, in the county of New York and State of New York, have invented a new, original, and ornamental Design for a Ring, of which the following is a specification, reference being had to the accompanying drawing, forming part thereof.

I claim:

The ornamental design for a ring, as shown.

In testimony whereof I affix my signature.

MAURICE J. SCHLESS.
